TEXTILE DRAFTING MECHANISM

Benjamin C. Shaw, Saco, Maine, assignor to Saco-Lowell Shops, Boston, Mass., a corporation of Maine

Application February 26, 1942, Serial No. 432,417

12 Claims. (Cl. 19—140)

This invention relates to drafting mechanisms and is more especially concerned with the clearers for the drawing rolls or equivalent drawing elements.

The prior art clearers in common use are of two types, namely, a flat clearer and a revolving clearer. The flat clearer, as its name implies, has an approximately flat surface supported in contact with several rolls or roll sections, and the clearer surface consists of a napped fabric or some material of that general nature adapted to clean the lint and fly off the drawing rolls with which it cooperates. The chief disadvantage of a clearer of this type is its relatively small storage capacity for the waste that it accumulates. Because of this fact, its capacity is exhausted after a relatively short period of operation, and any excess of waste thereafter delivered to it is very likely to drop off and eventually to get into the fiber being processed and thus produces a lump in the yarn. This relatively limited storage capacity therefore necessitates frequent removal and cleaning of the clearer itself.

Revolving clearers have a considerably larger storage capacity for waste than do flat clearers, but since they run in contact with and are revolved by the rolls which they are supposed to keep clean, they do not exert as effective a cleaning or polishing action on the drafting rolls as do the flat clearers. A further objection to revolving clearers is the fact that the lint and fly which they remove from a drawing roll is not attached firmly to the surface of the clearer, with the result that parts of the accumulated waste may drop back into the machine if, for any reason, the action of the clearer becomes erratic.

The defects above mentioned have long been recognized and are well known, and many attempts have been made to devise a clearer in which the advantages of the two types above mentioned would be combined and the disadvantages of both would be eliminated. So far as I am aware, however, none of these attempts has proved successful. The cone type of clearer is one example of such attempts, and a serious objection to it and to many of the others has been that they work the accumulation of lint and fly which they have removed from the drawing roll into small rolls, often referred to as "rat tails" or "cigarettes." These give trouble by dropping back into the machine and producing defective yarn.

The present invention is especially concerned with the conditions above described, and it aims

to devise a thoroughly practical solution for the old problem of providing a clearer having the advantages of the old types but avoiding their disadvantages.

6 The nature of the invention will be readily understood from the following description when read in connection with the accompanying drawings, and the novel features will be particularly pointed out in the appended claims.

10 In the drawings,

Figure 1 is a plan view of the front drawing roll of a spinning or roving frame and parts adjacent thereto, showing the machine equipped with a clearer roll embodying this invention;

15 Fig. 2 is a front elevation, partly in section, of the clearer roll shown in Fig. 1; and

Fig. 3 is a vertical, transverse, sectional view through a drawing mechanism for a spinning frame showing it equipped with a clearer roll like 20 that illustrated in Figs. 1 and 2.

Referring first to Fig. 3, the machine there shown comprises front, middle and rear bottom rolls 2, 3 and 4, respectively, and corresponding upper or top rolls 5, 6 and 7 running in contact

25 with and driven by the respective bottom rolls just mentioned. The particular number and arrangement of rolls employed is immaterial so far as this invention is concerned. In practically all of these drawing mechanisms the upper front roll collects considerably more fly than do any of the other rolls and the cleaning problem, therefore, is more troublesome at this point than at any other in the machine. Also, it is customary in these mechanisms to mount a single clearer roll in contact with three or four drawing rolls

30 of the top front line. The present invention is shown in the drawings as embodied in a clearer roll, indicated in general at 8, and provided with six cleaning sections a, each of generally cylindrical form, and adapted to run in contact with the fiber engaging surfaces of three of the top rolls 5, it being understood that in accordance with the usual practice each top roll has two bosses covered with leather or some other suitable 35 cushioning material.

40 The fundamental difference between applicant's clearer roll and those heretofore used is that while it is supported in a generally parallel relationship to the top rolls, it is not exactly parallel thereto but is disposed at a slight angle to them, as best illustrated in Fig. 1. That is, 45 the plane through the axis of the clearer roll at right angles to the 30° plane of the rolls themselves intersects the corresponding plane of the line of top rolls at an acute angle having a mag-

50

nitude, say, of from 1° to 3° , the line of intersection of said planes crossing the axis of the clearer roll at about the middle of the length of the latter.

The body of the clearer roll may consist of a steel rod, machined to approximately the form shown, or, more preferably, of a steel rod 8' on which a series of wood bosses 8" is secured. In either event the bosses are covered with clearer fabric and they run in engagement with the respective bosses of the top front line rolls. At its opposite ends the clearer roll has two gudgeons 9 and 10 resting in slots formed in two small brackets 12 and 13 which are secured to the upper surfaces of adjacent roll stands by screw and slot connections so that they can be adjusted forward and backward.

It will be observed that the geometry of this angular relationship between the clearer roll and the top rolls on which it works, requires that each clearer section be slightly larger at one end than the other, and that the intervening surface be slightly concaved. Actually, the degree of such concaving effect required is so slight as to be practically negligible. The roll, however, is naturally larger in diameter at its ends than at the middle, and the machined surfaces of the bosses are so tapered that homologous elements of the entire series of bosses lie in a common arc 14, as shown in Fig. 2.

It will readily be understood that when such a clearer roll is revolved by the line of top rolls on which it rests, each of the cleaning sections, except those at its ends, will exert a combination of a tangential rubbing action and a longitudinal rubbing or scuffing action on the surface of the top roll with which it is in contact. The tangential action is produced by the difference in surface speeds of the clearer and the top rolls, while the longitudinal rubbing action is produced by an end thrust component due to the angle between the axis of the clearer and that of the top rolls. The fact that this end thrust is actively working can readily be seen by placing the clearer in the frame as far to the left of the position shown in Fig. 1 as possible. As it begins to revolve it will immediately travel to the right as far as the right-hand bearing will permit it to go, and thereafter it will remain in this position. The greater the angle between the rolls the stronger will be this end thrust component. The combination of these two rubbing actions not only produces a very effective cleaning of the top rolls but it also works the lint and fly into a very dense felt-like mass which adheres strongly to the fibrous covers on the clearer bosses but can still be removed easily when desired. This operation, however, has the advantage of making use of the full lint holding capacity of the clearer so that it will run for a relatively long time without requiring stripping.

Experiments with the different angular relationships of the two rolls has indicated that the angle should be at least 1° and as a rule should not go over 5° . A larger angle has the disadvantage of obscuring the operator's view of the top rolls while a smaller angle reduces the effectiveness of the cleaning action.

It is important that such a roll be driven at a constant speed since irregular operation tends to produce "cigarettes" or "rat tails." It is preferable, therefore, to make the sections at the opposite ends of the roll sufficiently larger than the intervening sections so that these two

end sections will support the entire weight of the clearer and it will be driven by them. The fact that the intermediate bosses do not bear on their respective top rolls is not important so far as the cleaning action is concerned for the reason that the covers on these bosses are made of a lofty fabric and even if little more than the tips of the fibers of these fabric sections wipe the surfaces of the top rolls, that is sufficient to keep the latter clean. In this connection it may also be observed that the larger end bosses revolve at a higher surface speed than the intermediate sections and this fact is of advantage from a cleaning standpoint because the latter sections revolve at a slower surface speed than do their respective top rolls.

It should be noted that the gudgeons at the opposite ends of the roll are of different diameters, the right-hand gudgeons 10 being larger than the other, and the slot in the left-hand bracket 12 is made just wide enough to receive the smaller gudgeon so that the clearer must always be placed in the machine in the same way. This is of advantage in ensuring that the longitudinal felting action will always be in the same direction and thus will make a smoother and firmer sheet of waste than would be produced if the action were reversed by putting the clearer in first one way and then in the other. Thrust washers are positioned on the gudgeons to bear against the respective brackets.

It has been found in practice that a clearer of this type does combine the advantages of the two old forms of clearers above mentioned while avoiding the objectionable features of both.

While the drawings illustrate the invention as applied only to the front line top rolls, it will be understood that it may be used on any of the other rolls desired within the limits of the machine design, and this applies to bottom rolls as well as to top rolls. Usually it will be found more convenient, however, to use a stationary top clearer, such as that shown at 15, on the middle and back top rolls. In the drawings the degree of taper of the bosses is somewhat exaggerated, merely for purposes of illustration.

While I have herein shown and described a preferred embodiment of my invention, it will be evident that the invention may be embodied in somewhat different forms without departing from the spirit or scope thereof.

Having thus described my invention, what I desire to claim as new is:

1. In a drawing mechanism of the character described, the combination with a series of drafting roll sections arranged in axial alignment, of a clearer roll of generally cylindrical form but having circumferential cleaning surfaces tapering from opposite end portions of the roll toward an intermediate portion of smaller diameter than said end portions, and means supporting said clearer roll in contact with said drafting roll sections and in a generally parallel relationship thereto but with the plane of its axis intersecting the plane of the axis of said drafting roll sections at an acute angle of such magnitude as to produce both tangential and endwise rubbing actions on said drafting roll sections.
2. In a drawing mechanism according to preceding claim 1, a construction in which said angle is between one and five degrees.
3. In a drawing mechanism according to preceding claim 1, a construction including means

supporting the clearer roll against end thrust in one direction.

4. In a drawing mechanism according to preceding claim 1, a construction in which the supporting means for said clearer roll cooperates therewith to prevent the latter roll from being reversed with reference to the drafting roll sections.

5. In a drawing mechanism according to preceding claim 1, a construction in which the clearer roll comprises a plurality of cleaning sections spaced lengthwise of the roll, and the end sections are sufficiently larger in diameter than middle sections to drive the clearer roll substantially to the exclusion of the middle sections.

6. A clearer for drafting rolls comprising a roll having a plurality of cleaning sections to engage corresponding sections of a drafting roll, said clearer roll being smaller in diameter at intermediate cleaning areas than at opposite ends of the roll, homologous elements of said areas lying substantially in a common arc of a circle of relatively large radius.

7. A clearer for drafting rolls comprising a roll having a plurality of cleaning sections to engage corresponding sections of a line of drafting rolls, the end sections of said clearer roll being larger in diameter than intermediate sections said end sections being tapered slightly, with their smaller ends toward the middle of the roll.

8. A clearer for drafting rolls comprising a roll having a series of cleaning sections spaced longitudinally thereof to engage a corresponding series of fiber drafting sections of a line of drafting rolls, said cleaning sections being larger in diameter at opposite ends of the roll than

at an intermediate portion thereof, and elements of said sections lying substantially in a common arc of a circle.

9. In a drawing mechanism according to preceding claim 1, a construction in which said means supports said clearer roll for rotation by said drafting roll around a stationary axis.

10. In a drawing mechanism according to preceding claim 1, a construction in which said means supports said clearer roll for rotation around a stationary axis by said drafting roll and holds said clearer roll in an axially stationary position.

11. In a drawing mechanism of the character described, the combination with a drafting roll, of a clearer roll of generally cylindrical form but having circumferential cleaning surfaces tapering from opposite end portions thereof toward an intermediate portion of smaller diameter than said end portions, and means supporting said clearer roll in contact with said drafting roll and in a generally parallel relationship thereto but with the plane of its axis intersecting the plane of the axis of said drafting roll at an acute angle of small magnitude, the line of intersection of said planes passing through said intermediate portion of the clearer roll where it is of smaller diameter.

12. In a drawing mechanism according to preceding claim 1, a construction in which said clearer roll surfaces are spaced lengthwise of the roll and are shaped to engage approximately the entire lengths of the respective fiber working portions of said drawing roll sections notwithstanding the angular relationship between said sections and said clearer roll.
